Int. Cl. D21—01

U.S. Cl. D34—5 PP

FIG. 1 is an elevational view of either side of an apertured net for handball playing games showing my new design;

FIG. 2 is representative of both a top and bottom plan view of the net design herein;

FIG. 3 is a view similar to FIG. 1, but representative of a single apertured net embodiment;

FIG. 4 is a view similar to FIG. 1, but in which the net apertures are arranged reversely of those in FIG. 1;

FIG. 5 is a view similar to FIG. 1 but representative of a modified net design having two identical net apertures equally spaced from the constricted center of the net; and

FIG. 6 is a view similar to FIG. 1 but of a slightly different embodiment having three uniform sized net apertures therein.

The dominant feature of my design resides in the flared ends of the net and the pronounced constricted medial portion thereof in combination with the aperture arrangements as shown.

I claim:

The ornamental design for apertured net for handball playing games, as shown and described.
